US00D944055S

(12) **United States Design Patent** (10) **Patent No.:** **US D944,055 S**
Glessner (45) **Date of Patent:** **** Feb. 22, 2022**

(54) **FIXED BLADE KNIFE**

(71) Applicant: **Spyderco, Inc.**, Golden, CO (US)

(72) Inventor: **Louis Sal Glessner**, Evergreen, CO (US)

(73) Assignee: **Spyderco, Inc.**, Golden, CO (US)

(**) Term: **15 Years**

(21) Appl. No.: **29/784,010**

(22) Filed: **May 17, 2021**

(57) **CLAIM**

The ornamental design for a fixed blade knife, as shown and described.

DESCRIPTION

FIG. 1 is a perspective view of a fixed blade knife; FIG. 2 is a front elevation view thereof; FIG. 3 is a rear elevation view thereof; FIG. 4 is a left elevation view thereof; FIG. 5 is a right elevation view thereof; FIG. 6 is a top plan view thereof; FIG. 7 is a bottom plan view thereof; FIG. 8 is a cross-sectional view taken at line 8-8 of FIG. 2; FIG. 9 is a cross-sectional view taken at line 9-9 of FIG. 2; and, FIG. 10 is a cross-sectional view taken at line 10-10 of FIG. 2.

The broken lines depict portions of the fixed blade knife in which the design is embodied that are not considered part of the claimed design.

1 Claim, 5 Drawing Sheets
